UNITED STATES PATENT OFFICE.

LESLIE A. COOPER, OF SPRINGFIELD, MASSACHUSETTS, ASSIGNOR OF ONE-
THIRD TO ALVAH H. SABIN, OF NEW YORK, N. Y.

OIL-SEPARATING APPARATUS FOR STEAM-ENGINES.

SPECIFICATION forming part of Letters Patent No. 655,610, dated August 7, 1900.

Application filed January 8, 1900. Serial No. 645. (No model.)

To all whom it may concern:

Be it known that I, LESLIE A. COOPER, a citizen of the United States of America, and a resident of Springfield, in the county of 5 Hampden and State of Massachusetts, have invented certain new and useful Improvements in Oil-Separating Apparatus for Steam-Engines, of which the following is a full, clear, and exact description.

10 This invention relates to improvements in oil-separators for steam-engines.

As is well known, in the running of certain types of steam-engines, more especially, although not exclusively, in steam-engines of 15 the rotary-piston and rotary-abutment types, oil is copiously introduced into the engine with the steam for lubrication of the rotatable running parts and which oil passes from the interior of the engine with the 20 exhaust-steam.

The object of this invention is to provide, in conjunction with a rotary-piston engine or other type of engine, means for the separation and reclamation of the oil from the 25 exhaust steam, whereby such recovered oil may be used over and over again.

The invention consists in the device or apparatus which constitutes the oil-separator and which is hereinafter fully described, and 30 set forth in the claims.

The improved separator is illustrated in the accompanying drawings, in which—

Figure 1 shows the separator in the cross-sectional representation of a concentric-piston 35 ton rotary steam-engine. Fig. 2 is a plan view of a rotary steam-engine and horizontal sectional view through the separating apparatus therewith combined, a part of the rotary brush-like appliance being broken away 40 for clearer illustration. Fig. 3 is a plan view of the aforesaid brush-like appliance. Figs. 4, 5, and 6 are perspective views of details of constructions comprised in the separator.

Similar characters of reference represent 45 corresponding parts in all the views.

It is to be understood that the steam, with lubricating-oil, is supplied to the engine in the usual manner and is exhausted therefrom through the exhaust-port *g*, whereupon it enters the end portion of the comparatively-long cylindrical chamber *G*, which may prac-

tically be comprised within the same casting which forms the engine-case. The said chamber has end heads to constitute journal-bearings for the shaft *50*, surrounding which is 55 the tubular core *52*, having a multiplicity of perforations *53*, in which are anchored or attached a corresponding number of radial wires 54, extending to or near to the internal wall of the chamber *G*. 60

At suitable intervals along the length of the brush-like appliance are ring-plates *h*, preferably formed in half-sections with angularly-turned lips *55*, united by bolts or rivets. These ring-plate sections are supported by 65 arms *56*, carried by sectional hubs *57*, which are clamped about the core *52* by the screws, bolts, or rivets *58*.

Along the base of the casing in which is the chamber *G* is the channel *59*, the same downwardly opening at one end thereof to the oil-receiver *H*, while at the end of the casing *G* opposite that at which the steam is exhausted thereinto is the final steam-discharge conduit 60. 70

The shaft *50* is driven by the externally-applied gearing *62* *63*, shown as run from the gear *j* on the rotary abutment-shaft.

The admixed steam and oil entering the initial end of the casing *G* is caused by the 80 ring-plate to necessarily mainly pass along through the brush near its core. The mist-like particles of oil are arrested by and collected on the wires and by the centrifugal action thereof thrown outwardly against the 85 surrounding wall of the chamber *G* and run down to the bottom thereof into the channel *59* and thence into the receiver *H*. As the steam will have a tendency to work toward the wall of the chamber, the succession of the 90 ring-plates are provided at suitable intervals, as before mentioned, to constitute a steam-break, so that it will have its course diverted several times toward the core of the brush to give all portions of the latter opportunity to 95 exert its oil-collecting action before the steam passing through the chamber *G* reaches the final discharge-passage *60*. In addition to the rotary wires or collecting members *I* may also employ non-rotary wires or collecting 100 members *61*, which may be advantageously supported in and extended upwardly above

the base of the drain-channel 59 into the chamber G and lapped beyond the ends of the revoluble wires, a vacant annular place or space 62 being left in the brush-like appliance to accommodate these stationary wires or projections. The purpose of these stationary wires or projections will be explained as follows: The steam after having entered within the brush-wires will after a while have developed a revoluble motion more or less nearly in consonance with the brush-wires, whereby the beating action by the brush-wires on the steam and the oil elements therein becomes lessened.

15 The provision of the stationary wires or members projecting from the wall of the case well toward the core of the brush constitute not only additional parts against which the steam will impinge and upon which deposit 20 more or less of the contained oil, but will counteract and lessen the revoluble and centrifugal motion of the steam, whereby the latter in its continued course through the brush-wires will be by the latter more efficiently 25 whipped, and will consequently insure that the said brush-wires will collect thereon a greater proportion of the oil which is held in suspension by the steam passing therethrough.

30 The series of stationary steam-breaking appliances may be duplicated at suitable intervals in the separating apparatus, the rotary device being correspondingly constructed for the accommodation thereof.

35 The description of engine on which this invention is applied is illustrated and claimed in an application for Letters Patent of the United States filed by me October 27, 1899, Serial No. 734,902; but it is to be understood 40 that the herein-described oil-separating apparatus is available in connection with other types of engines.

Having thus described my invention, what I claim, and desire to secure by Letters Patent, is—

45 1. An oil-separating apparatus for a steam-engine consisting of a casing with steam inlet and outlet openings leading thereto and therefrom, a rotary appliance therein of pervious formation, whereby it is longitudinally penetrable by the steam, and also radially 50 pervious, whereby it will project accumulations of condensed steam and oil toward the wall of the casing, means for the rotation of said appliance, and an oil-collection receptacle in communication with the interior of the 55 said casing.

2. In an oil-separating apparatus, a closed

casing or chamber, having steam inlet and outlet ports at opposite portions thereof, a 60 rotary oil collecting or arresting and centrifugally-projecting device having at an intermediate part thereof an unobstructed or vacant space, and a stationary steam-breaking device which projects within the said vacant 65 space in the rotary device.

3. An oil-separating apparatus for a steam-engine consisting of a casing with steam inlet and outlet openings leading thereto and therefrom, a rotary brush-like appliance 70 therein, and means for the rotation thereof, and an oil-collection receptacle open to the said casing.

4. An oil-separating apparatus consisting of a chambered casing, a rotary shaft extending through the casing having the multiplicity of radial wires with steam-breaking sections at intervals and an oil-collecting receptacle 75 open to the chamber in the casing.

5. An apparatus for separating the oil from the steam exhausted from an engine consisting of a casing having an opening for the entrance of the admixed exhaust-steam and oil, a rotary appliance therein, a drainage-conduit, and means for rotating the said appliance. 80

6. An oil-separator for a steam-engine consisting of a chambered casing having a drainage-channel, a rotary shaft within said casing having the multiplicity of radial wires or members and at intervals annular steam-breaking sections, for the purposes set forth. 85

7. An oil-separating apparatus for a steam-engine consisting of the cylindrical chamber-casing G, the rotatable shaft therein, and 90 means for turning it, said shaft being provided at intervals with the radial arms supporting the ring-plates and having between the several ring-plates, radial wires arranged brush-like, a drainage-channel in the base of the chamber and an oil-receiver into which said channel leads. 95

8. An oil-separator for a steam-engine consisting of a chambered casing, a rotary shaft within said casing having a multiplicity of radial wires or members and at intervals annular steam-breaking sections, and a series of non-rotating members within said casing 100 projecting toward the axis of said shaft.

Signed by me at Springfield, Massachusetts, 110 this 29th day of December, 1899.

LESLIE A. COOPER.
